C. Snowdon.

UNITED STATES PATENT OFFICE.

GEORGE PETTER, JR., OF PADUCAH, KENTUCKY.

DRUM.

SPECIFICATION forming part of Letters Patent No. 440,192, dated November 11, 1890.

Application filed December 19, 1889, Serial No. 334,317. (No model.)

To all whom it may concern:

Be it known that I, GEORGE PETTER, Jr., a citizen of the United States, residing at Paducah, in the county of McCracken and State of Kentucky, have invented a new and useful Drum, of which the following is a specification.

This invention relates to improvements in drums.

10 The object of the present invention is to simplify and improve the means employed for bracing the heads of drums and enable the heads to be braced separately, and to be quickly removed and replaced by new ones when necessary.

15 The invention consists in the construction and novel combination and arrangement of parts, illustrated in the accompanying drawings, and particularly pointed out in the claims hereto appended.

20 In the drawings, Figure 1 is a perspective view of a drum provided with bracing means constructed in accordance with this invention. Fig. 2 is an enlarged side elevation. Fig. 3 is a detail view of one of the hooks. Fig. 4 is a similar view of one of the stationary rollers that are secured to the cylinder of the drum.

25 Referring to the drawings, 1 designates the cylinder, which constitutes the body of the drum and is constructed of any suitable material, either wood or metal, and is provided at its top and bottom with hoops 2 and 3, that secure the head 4 and the reverse or snare head 5 to the ends of the cylinder 1, and are engaged by removable hooks 6, that are provided with openings 7, in which are arranged pulleys 8, over which pass cords 9 and 10, that tighten the heads and regulate the tone of the drum. The head 4 and the reverse or snare head are constructed in the usual manner, and are attached at their edges to wooden rings or bands 11 and 12, that encompass the cylinder and slide upon it, and are secured in place by the hoops 2 and 3. The cylinder 1 is provided near its end with rows of stationary pulleys 13, that are arranged in pairs, and the rows are designed to be engaged, respectively, by the cords 9 and 10, that pass over the pulleys 8 of the hook 6. Each of the cords

9 and 10 engages a set of hooks arranged upon one of the hoops, and passes over the pairs of pulleys that are arranged farther from the hooks and at the opposite end of the drum, whereby the heads of the drum are enabled 55 to be braced independently, thereby insuring a much finer tone than would be the case were the head braced in the ordinary manner. Each cord is provided with a series of leather loops or sliders 13*, which are arranged between the hooks and the opposite row of pulleys and embrace the cord and operate in the usual manner, the hooks being arranged opposite the intervals between the farther pairs of stationary pulleys, whereby 65 when the leather loops 13* are moved toward the stationary pulleys the cord will be drawn taut and the head of the drum tightened.

70 From the foregoing description and the accompanying drawings it will readily be seen that the means employed for bracing the drum-head are simple and inexpensive in construction, adapted to be readily applied to the ordinary form of drum, enable the drum-heads to be braced independently, and permit the drum-heads to be readily removed when desired.

75 Having thus described my invention, what I claim, and desire to secure by Letters Patent, is—

80 1. The combination, with the drum, of the rows of stationary pulleys arranged in pairs at the top and bottom of its cylinder, the hooks arranged upon the bracing-hoops, and the cords 9 and 10, engaging the hooks and the 85 opposite rows of pulleys, substantially as and for the purpose described.

85 2. The combination, with the drum, of the rows of stationary pulleys arranged in pairs near the top and bottom of the cylinder, hooks 90 engaging the bracing-hoops and provided with pulleys, and the cords 9 and 10, passing over the pulleys of the hooks and the opposite row of stationary pulleys, substantially as and for the purpose described.

95 3. The combination, with the drum, of the stationary pulleys arranged in pairs near the top and bottom of the cylinder, the hooks engaging the bracing-hoops and arranged opposite the intervals between the pairs of pul- 100

leys at the other end of the drum, the cords 9 and 10, passing over the pulleys of the hooks and the pairs of pulleys at the opposite end of the drum, and the leather loops 13, adapted to tighten the cords, substantially as and for the purpose described.

In testimony that I claim the foregoing as

my own I have hereto affixed my signature in presence of two witnesses.

GEORGE PETTER, JR.
